BAG FRAME LATCH

William C. Hiering, Newark, N. J., assignor to
 J. E. Mergott Company, Newark, N. J., a corporation of Delaware

Application October 6, 1934, Serial No. 747,149

3 Claims. (Cl. 292—19)

This invention relates to frames for ladies' hand bags and more particularly to improvements in means for assembling elements of latching devices used in connection with such frames.

5 Heretofore, elements of latching devices as used on handbag frames have been connected by means of small rivets, solder or the like, resulting in a somewhat unstable structure incapable of effectively withstanding rough handling or 10 extended use, with the result that after a certain period the solder would break, causing the elements to fall apart.

It is an object of this invention to provide means for stably connecting elements of latching 15 devices for use on handbag frames, which means comprise substantially the striking out of a portion of the metal of one element to form a tab which is bent over the other element to securely hold said elements together.

20 A further object is the provision of a method of joining a substantially flat metal element to a substantially bulky metal element.

These and other advantageous objects, which will later appear, are accomplished by the simple 25 construction, combination and arrangement of parts hereinafter described and shown in the accompanying drawing, forming part hereof and in which:

30 Fig. 1 is an elevational view of handbag frame members having attached thereto latching devices embodying my invention.

Fig. 2 is a plan view of the underside of one of the latching members shown on the frame in 35 Fig. 1.

Fig. 3 is a sectional view of the latching member shown in Fig. 2.

Fig. 4 is a side elevational plan view of an element of the latching member shown in Figs. 2 40 and 3.

Fig. 5 is a sectional view taken on line 5—5 of Fig. 3.

Fig. 6 is a perspective view, partly in section, showing the manner in which elements of the 45 latching member are connected together.

Fig. 7 is an elevational view showing a modified form of latching device attached to a frame member.

Fig. 8 is a perspective view showing elements 50 of the latching device of Fig. 7.

Fig. 9 is a perspective view showing the manner in which the elements of Fig. 8 are connected together.

55 Referring to the drawing, in Fig. 1 frame members 10 for a lady's hand bag, are shown, to which

are attached supports 11 for cooperating latching members 12.

Each of the latching members 12 comprises substantially a block of metal, preferably formed from extruded stock in any desired shape, to which is attached the flat support 11, which is provided with tabs 13 adapted to pass through suitable apertures in the frame member 10, after which the tabs 13 are bent over the frame member to securely hold the support 11 thereto. 10

The support 11 is provided with a narrow head 14 which is positioned in a groove 15 in the member 12, the groove 15 being substantially the same width as the head 14 so that the latter fits snugly in the groove. After the head 14 is positioned 15 in the groove 15, small tabs 16 are struck or cut from the side walls of the groove by means of a punch or similar tool, the tabs 16 being bent over the head 14 as shown in Fig. 6 to securely hold 20 the head in the groove and substantially permanently connect the support to the member 12.

From the above description it will be seen that the connection between the elements 11 and 12 is of such a stable and rigid character that the latching device will withstand long and rough 25 usage, much more effectively than would be the case were the elements connected by means of solder or the like as has heretofore been the practise. At the same time, my manner of connecting the elements together is much simpler 30 than a soldering operation as the tabs can be cut from the walls of the groove and bent over the head 14 all in one operation.

Figs. 7, 8 and 9 show an application of my invention to a modified form of latching device 35 which comprises a supporting element 17 having a pair of hinge members 18 which pass through apertures in the frame member 19. The hinge members receive a spring wire 20 in a manner well known and common in latching devices. 40 A latching member 21, comprising a substantially solid block of metal, is provided with a groove 22 which receives the supporting element 17, the latter being securely attached to the block 21 by striking tabs 23 from the walls of the 45 groove 22, and bending the tabs over the element 17 as shown in Fig. 9. By means of this structure I am enabled to readily, conveniently and rigidly connect the members 21 and 17 together in a 50 stable and permanent manner, without the use of rivets, solder or the like.

It will be seen that my invention is especially applicable to the joining together of elements where it is impracticable or impossible to use rivets. For example, it would be extremely im- 55

practicable to connect the head 14 to the solid block of metal 12 by means of rivets, and solder or a similar substance would have to be resorted to.

5 By means of my invention, I am able to make a connection between the two elements which is as strong as if not stronger than connections which might be obtained by rivets or otherwise.

10 The foregoing description is to be regarded as descriptive and illustrative only, and not as restrictive or limitative of my invention, of which obviously an embodiment may be constructed including many modifications within the scope of my invention as set forth in the appended claims.

15 Having thus described my invention, what I claim as new and desire to secure by Letters Patent, is:

1. In a latching device for hand bag frame members, a supporting element adapted to be secured to a frame member, a latching member having a groove therein to receive the supporting element, and tabs cut from the side walls of the groove, said tabs being substantially parallel to

the bottom of the groove and engaging the supporting element to securely hold the parts together.

2. In a latching device for a hand bag frame member, a supporting element adapted to be secured to a frame member, said supporting element having a head, a latching member comprising a block of metal having a groove therein to snugly receive said head, and tabs cut directly from the side walls of the groove in the block, 10 said tabs overlying said head substantially parallel to the bottom of the groove, to securely hold the supporting element and block together. 5

3. In a latching device for a hand bag frame member, a supporting element adapted to be secured to a frame member, said supporting element having a head, a latching member comprising a block of metal having a groove therein to snugly receive said head, and tabs cut directly from the side walls of the groove in the block, 20 said tabs overlying said head to securely hold the supporting element and block together. 15

WILLIAM C. HIERING.
